[57] CLAIM

The ornamental design for a multi compartment display, as shown and described.

DESCRIPTION

FIG. 1 is a front perspective view of a multi compartment display showing our new design;

FIG. 2 is a side elevational view of the left-hand side thereof, the right-hand side view being a mirror image of FIG. 2;

FIG. 3 is a top plan view thereof;

FIG. 4 is a front elevation view thereof; and,

FIG. 5 is a bottom plan view of our new design for a multi compartment display.
